INVENTOR
ARTHUR R. RYAN.

BY *Fetherston and Son* *AT 1175*

UNITED STATES PATENT OFFICE.

ARTHUR ROBERT RYAN, OF CALGARY, ALBERTA, CANADA.

DOOR DEVICE.

1,404,238.

Specification of Letters Patent. Patented Jan. 24, 1922.

Application filed March 30, 1921. Serial No. 456,896.

To all whom it may concern:

Be it known that I, ARTHUR ROBERT RYAN, a subject of the King of Great Britain, and resident of the city of Calgary, in the Province of Alberta, Dominion of Canada, have invented certain new and useful Improvements in Door Devices, of which the following is a specification.

This invention relates to a door device, and the objects of the invention are to provide a device which will open and close double or single doors at the same time, also holding doors apart when open, thus preventing the doors from blowing closed.

Other objects are to provide a means whereby the mechanism to lock the door can be easily operated, and further objects are to provide a device that is simple in construction and not liable to go out of repair, and generally to adapt the several parts to better perform the functions required of them.

With the above and other objects in view, the invention consists essentially of the improved construction particularly described and set forth in the following specification and accompanying drawings forming part of the same.

In the drawings:

Figure 1 is a vertical section through a door embodying my invention.

Figure 2 is a plan view of a pair of double doors designed to open outwardly and embodying my improved device.

Figure 3 is a perspective view of the car.

Figure 4 is an enlarged sectional view of the door lintel with the rail and improved device connected thereto.

Figure 5 is a cross section taken on the line 4—4 of Figure 4.

Figure 6 is a longitudinal section taken on the line 5—5 of Figure 5.

Figure 7 is a plan view of a pair of double doors adapted to open inwardly and provided with the improved locking means.

Like characters of reference refer to like parts in the several figures.

Referring to the drawings, A represents a pair of double doors, and B the door lintel, and C indicates the ceiling of the car.

An iron track 10 is carried by the underside of the door lintel B, and extends parallel to the ceiling and is supported at the outer end with an adjustable strap iron brace 11 carried by the ceiling.

A car D is designed to run on the track

10 and consists essentially of two plates 12 and 13 connected by pins 14 carrying rollers 15 designed to engage the side faces of the rail 10.

The top plate 12 is provided with two projections 16, the purpose of which will be made clear hereafter.

The car D also carries on either side of the rail 10, the upwardly turned end of two iron bars 17 and 18 extending angularly and connected to projecting lugs 19 and 20 carried by the top part of the doors A.

The rail 10 is provided at one end adjacent the door lintel B with a clamp 21 pivotally carrying a latch member 22 having a notch 23 therein designed to engage one of the projections 16 on the car D when the same is moved in proximity to the said latch.

The outer end of the track 10 adjacent the brace 11 is also provided with a clamp 24 carrying a latch member 25 and notch 26 also designed to engage one of the projections 16 provided on the top plate 12 of the car D.

Each of the latches 22 and 25 are provided on the top face thereof with a ring 27 through which a rope or wire 28 passes. The rope or wire 28 is fastened at one end to the adjustable brace 11 and extending parallel to the rail 10 through the rings 27 engages an eye 29 carried by the door lintel B and extends downwardly and has its extremity provided with a handle 30 by the handling of which the latches 22 and 25 may be worked.

When in use and if the doors are closed as shown in Figure 4, the latch 25 will be in engagement with the projection 16 on top of the plate 12 of the car D, and should it be desired to open the doors A, the rope 28 is pulled downwardly so as to disengage the latch 25 from the projection 16 when the doors will open, on slight pressure being applied against them.

As soon as the car D travelling on the rail 10 passes under the latch 22, the hold on the rope 28 is released and the latch 22 will be lowered and thus caused to engage the second projection 16 on top of the car thereby locking the doors in open position.

It will be seen that the device can be adapted to double swinging doors, when the car and latches 18 and 17 will take the position shown in Figure 2 in dotted lines. Whereas they will adopt the position shown

in dotted lines in Figure 7 when they are swung inwardly.

The device is herewith shown connected to a barndoors, but it will be understood that the same can be suitably worked in connection with any door and even with a single door.

The clamping members 21 and 24 may be slidably mounted on the rail 10 and provided on the underside with a thumb screw 31 by means of which it can be fastened in position on the rail. It will be seen by this means the doors can be opened to the desired degree and locked in that position.

When the doors are adapted to swing outwardly and inwardly, the lugs 19 and 20 are made to extend higher than the door so as to allow the same free passage under the rods 17 and 18 when the doors are open inwardly as shown in dotted lines in Figure 7.

As many changes could be made in the above construction, and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:—

1. A door locking device comprising in

combination with a door, a rail having one end fastened to the door jamb, a brace supporting the opposite end of the rail, a car in slidable engagement with the rail and comprising a top plate, a lower plate, pins holding the plates above and beneath the rail, rollers on the pins designed to engage the rail, a rod on the door having one end engaging the car, projections on the top plate, latches carried by the rail and means to bring the latches in and out of engagement with the projections.

2. The door locking device claimed in claim 1, in which the latches are carried by clamps slidably engaging the rail, and a thumb screw on the clamps to fasten the same to the rail.

3. The door locking device claimed in claim 1, in which the latches are each provided with a ring, a wire extending through the rings and having one end fastened to the brace, an eye on the door jamb designed to engage the downwardly extending end of the wire, and a hand grip on the end of the wire.

In witness whereof I have hereunto set my hand in the presence of two witnesses.

ARTHUR ROBERT RYAN.

Witnesses:

W. L. ALLEN SCOTT,
FRANCES NOBLE.
